(57) **CLAIM**

The ornamental design for a low profile retractable lanyard, as shown and described.

DESCRIPTION

FIG. 1 is a perspective view of a low profile retractable lanyard showing our new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a left elevation view thereof; and,

FIG. 7 is a right elevation view thereof.

The broken lines depict an environment of use and form no part of the claim.
